MEDICAL LIQUID BAG

Byron H. Wickett, North Hollywood, Calif., assignor to American Hospital Supply Corporation, Evanston, Ill., a corporation of Illinois

Filed Nov. 24, 1967, Ser. No. 9,532

Term of patent 14 years

(Cl. D83—1)

FIG. 1.

FIG. 2.

FIG. 3.

FIG. 1 is a front elevation of a medical liquid bag, showing my new design—the undisclosed rear is a mirror image of the front;

FIG. 2 is an end elevation as seen from the right of FIG. 1; and

FIG. 3 is a top plan view thereof.

The dominant features of my invention reside in those portions of the medical liquid bag shown in full solid lines.

I claim:

The ornamental design for a medical liquid bag, as shown and described.
